N° 8,912.

T. J. Sloan,
Steam-Boiler Indicator.

Patented Apr. 27, 1852.

UNITED STATES PATENT OFFICE.

THOMAS J. SLOAN, OF NEW YORK, N. Y.

FLOAT-GAGE, FEED-REGULATOR, &c., FOR STEAM-BOILERS, &c.

Specification of Letters Patent No. 8,912, dated April 27, 1852.

To all whom it may concern:

Be it known that I, THOMAS J. SLOAN, of the city, county, and State of New York, have invented certain new and useful Improvements in the Method of Indicating and Regulating the Height of Water in Steam and other Boilers, which said improvements are also applicable to all other vessels in which it may be desired to indicate and regulate the height of water and other fluids, and that the following is a full, clear, and exact description thereof, reference being had to the accompanying drawings, making part of this specification, in which—

15 Figure 1, represents a front elevation of my improvements as applied to a steam boiler; Fig. 2, an inside view of the head of the boiler; Fig. 3, a longitudinal vertical section of the boiler; and Fig. 4, a section 20 representing a modification.

20 The same letters indicate like parts in all the figures.

As it has been generally admitted that the deficiency of water is one of the principal causes of explosion of steam boilers, many inventions have been made for the purpose of indicating the deficiency and regulating the supply with the view to prevent explosions, but so far without success. Any 25 apparatus for this purpose to be good and useful, must be unerring in its operation, otherwise it will be positively bad, for it will be relied on by the attendant who will substitute its working for his own attention 30 and thus occasion many accidents which his vigilance might prevent. A float has generally been resorted to, as the means of indicating the level of water within the boiler and of communicating motion to the mechanism 35 for regulating the supply of water; but as the float is within the boiler, and the indicator and machinery for regulating the supply is outside, a connection has always been made through the shell of the boiler, 40 which, to prevent the escape of water and steam, must be packed, and which therefore from friction and varying strain and the liability to clog prevents the freedom of play of the float, and destroys that sensitiveness 45 indispensable to an accurate indication of the varying level of water in the boiler. And the use of the float as a means of communicating the required motion to an alarm or to the apparatus which effects or regulates 50 the supply, throws too heavy a duty

on the float which is in this way prevented from following the varying level of the water. It is important therefore to have the float and all its connections within the boiler so that it shall be free and sensitive to 55 follow the varying level of the water, and that it shall not be employed to give a visible indication of the level of water or to operate an alarm or the apparatus which supplies or regulates the supply of water, 60 but simply to check or control a mechanism which is to be impelled by a motive force outside and independent of the float. And to these ends the nature of my invention 65 consists in the employment of an independent float within a steam or other boiler or other vessel, which as its position is varied by the change of level of the water, shall act as a stop or check to the motions of a mechanism operated by an independent motive force outside the boiler, and thus by 70 varying the point of stop or check by the varying level of the water cause the independent motive force whatever it may be to act directly on the apparatus that supplies the water, to increase or check the supply, or an indicator, or a whistle or other alarm. And my invention also consists in 75 having said float hung to one arm of a rock shaft, when the said shaft is provided with another arm which acts as the stop or 80 check to determine the range of motion of the mechanism operated by the independent motive force outside the boiler so that when 85 such mechanism is brought in contact with 90 and is checked by the said arm of the float, it shall not affect the position of the float.

In the accompanying drawings *a*, represents the head of a steam boiler, and *b*, a float within the boiler, and attached to the outer end of an arm *c*, of a rock shaft *d*, which is hung in suitable bearings so as to be free to act. To avoid the deposit of sediment on the journals which might impede its free motion, the rock shaft may be 95 hung above the high water mark. This rock shaft carries another arm *e*, which at its outer end has an eccentric segment or tangent piece *f*, with teeth on its edge. So far all this is entirely within the boiler and 100 needs no packed joints, so that the float will be free to move with the varying level of water. Another rock shaft *g*, passes through the boiler and should be provided in the usual manner with a packed joint to prevent 105 110

the escape of steam or water. The outer end of this shaft carries an arm *h*, which is drawn or forced downward by a spring *i*, or weight or other equivalent force which must be sufficient to overcome any friction or check due to the packing of the joints or any tendency which they may have to adhere. On the outer end of this arm there is a wrist pin *j*, which is embraced by an elongated hole or slot *k*, in a rod *l*, which is to be connected with and operated by some motor. If the boiler be used for a steam engine, then this rod *l*, can receive the required reciprocating motion from some part of the engine, or it can receive the required motion from a crank (*l'*) kept in motion by a train of wheels and spring or weight as represented in the drawings at *m'*. But however the motion be communicated, the rod *l*, must be kept in motion so that as it is drawn in the direction of the arrow it will lift up the arm of the rock shaft, and on the return motion permit it to be drawn down by the spring *i*. On the inner end of the said rock shaft and within the boiler there is another arm *m*, with a pin *n*, so located as to come in contact with the teeth on the stop arm of the float, and thus check or stop the downward motion of the arm, and as the toothed face of the arm is eccentric or forms an inclined plane, the arm will be checked or stopped sooner when the float is up than when it is down, and as the rod *l*, on the outside slides on the wrist pin of the outer arm, the direction of the motion of this rod as it reciprocates will be varied, and be made to act variously for the supply of water. As for instance, when the float sinks down to the dotted line *o*, below low water mark, which indicates a dangerous condition of the boiler, the rod *l*, will act on a lever *p*, which is to be connected with a whistle or other alarm to call the attention of the engineer, &c. When the float is carried too high, say to the dotted line *q*, above the high water mark, the rod *l*, acts on another lever *r*, connected with the same or some other alarm.

Between the two alarm levers *p*, and *r*, there is another lever *s*, with its two arms inclined to each other and provided with teeth resembling ratchet teeth. This lever can be attached to a stop-cock, valve or other apparatus for regulating the flow of water into the boiler. The end of the rod *l*, is formed to act on the teeth of the lever *s*, and as the float continues to sink from the true water level, the rod continues to act further and further on the lower arm of the lever *s*, and hence to increase the supply of water. And as the float continues to rise from the true water level the rod *l*, will have the reversed action on the lever *s*, and hence gradually close the supply cock or valve and thus reduce the supply. In this way it will

be seen that the float is perfectly free to follow the level of the water except during the instant of time that the arm of the rock shaft is stopped by the stop arm of the float, and then as the action on the stop arm is in a radial or nearly radial direction and the stop arm is provided with teeth, the independent motive force outside can have no tendency to change the position of the float which is again released and free to follow the level of water in the boiler. As the motion of the rod for operating the supply apparatus or the alarm is derived from the engine or some independent motor, any amount of force can be given to it to insure working. And finally as the rocker which acts on the stop arm of the float, and which guides the rod that acts on the supply apparatus or the alarms is worked in one direction by the independent motor, and in the other by a spring or weight or in both by the independent motor, it will be obvious that there can be no danger of this motion being arrested or checked by the packing or sticking of the joints.

It will be obvious that instead of the spring *i* or weight for drawing down the arm *h*, of the rock shaft, that this can be done as represented in section (Fig. 4,) by a spring *t*, interposed between the wrist pin *j*, of the arm *h*, and the inner end of the slot in the rod *l*.

It will be obvious that this method of indicating the level of water and regulating the supply or giving an alarm can be applied to all kinds of boilers, such as boilers for heating houses and to any vessels in which it may be desired to indicate the height of water and regulate the supply.

The mechanism operated by any motive force and which is regulated in its motions or positions can be employed to operate any kind of indicator, alarm or water feeding or regulating apparatus.

I do not wish to be understood as limiting myself to the construction and arrangement of parts hereinabove described, as these may be varied without changing the principle or mode of operation of my invention.

I am aware that a float placed within a boiler or within a vessel communicating with a boiler has been employed to regulate the position of ratchet hands operated by an independent mechanism to open and close a valve, cock, or regulate the motion of a pump, the said float being employed simply to engage or disengage the said ratchet hands, but when so employed the said float has been so arranged as to act on the said mechanism outside the boiler, &c., and hence subjected to the difficulties above pointed out. I do not therefore claim broadly the employment of a float to regulate the action of an independent mechanism as a means of indicating the height of water and regulat-

ing the supply thereof, when such float acts upon such mechanism outside of the boiler. But

5 What I do claim as my invention and desire to secure by Letters Patent is—

10 1. The employment substantially as described, of an independent float within a steam or other boiler, or other vessel, which as its position is varied by the change of level of the water, shall act as a check or stop to the motion of a mechanism combined therewith, and operated by an independent motive force outside of and passing through to the inside of the boiler, substantially as

described to determine the supply of water 15 to be given or to give the required indication or alarm, as specified.

2. And I also claim the method herein described of preventing the action of the mechanism outside, which is actuated by an 20 independent force from reacting on and changing the position of the float, that it (the float) may be free to follow the varying level of the water as specified.

THOS. J. SLOAN.
